UNITED STATES PATENT OFFICE.

ERASTUS W. WILLARD, OF JOLIET, ILLINOIS, ADMINISTRATOR OF HAROLD R. WELLMAN,
DECEASED.

OSCILLATING FAN-MOTOR.

No. 888,435

Specification of Letters Patent.

Patented May 19, 1908.

Application filed March 30, 1906. Serial No. 308,879.

To all whom it may concern:

Be it known that I, ERASTUS W. WILLARD, administrator, a citizen of the United States, residing at Joliet, in the county of Will and State of Illinois, am in possession of an invention in a certain new and useful Improvement in Oscillating Fan-Motors, invented by HAROLD R. WELLMAN, deceased, of which the following is a full, clear, concise, and exact act description.

This invention relates to an oscillating motor driven fan, and has for its object to provide improved means for effecting the oscillatory movement of the fan.

Generally speaking, this invention contemplates a reciprocally-mounted motor driven fan provided with movable vanes carried upon the guard casing of the fan blades, said vanes being adapted to alternately screen the sides of the front of the fan, thus producing an unbalanced effect in the beam of air delivered, causing the fan to oscillate or turn from one side to the other as it rotates. Means are provided, actuated in the oscillation of the fan, for operating said vanes.

The invention will be more particularly described by reference to the accompanying drawings, which illustrate the preferred form of the invention, reference being had to the appended claims for a statement of the parts, improvements and combinations which are deemed novel.

In the drawings, Figure 1 is a front view of an oscillating fan embodying the invention; Fig. 2 is a sectional plan view on line 2-2 of Fig. 1; Fig. 3 is a longitudinal sectional view on line 3-3 of Fig. 1; and Fig. 4 is a detail perspective view of the spiral cam.

Similar letters of reference designate like parts throughout the several views.

The fan shown as equipped with my invention belongs to a well-known type of electrically operated fans, the motor, however, being pivoted to permit its oscillating movement. The guard casing *a*, which protects the fan blades, carries a pair of movable vanes *b* *b'*, which are preferably mounted on a common axis by means of pivotal rods *b*² *b*³, respectively. The outer ends of said rods are provided with bearings *b*⁴ carried by the frame, while the inner ends of said rods are secured to opposite ends of a cam *c*, which is adapted to be operated by the pendulum lever *d* to reverse the positions of said vanes. The vanes are mounted in planes at right an-

gles to each other so that said vanes will alternately occupy vertical and horizontal positions, respectively. Thus when the vane *b* is in a vertical position, which condition would result when the fan reaches the limit of its movement to the left, the left side of the front of the fan would be screened, and the air delivered by the fan would produce an unequal reaction thereon, the most reaction being present upon the unscreened side, which would cause the fan to swing to the right.

The lever *d* is arranged to be operated by arms *e* *e*, carried by the base of the fan, as the fan approaches the limit of its movement in either direction, to actuate said cam *c* and reverse the position of the vanes, in order that the fan may be swung in the reverse direction. The pendulum lever *d* is pivoted to the top of the guard casing and extends downwardly, through opposing spiral grooves *c* in the cam *c* into position to be engaged by the arms *e*, cross bars *a* *a'* of the guard *a* coöperating with said lever *d* and stops *e* to limit the movement of the fan. The lever *d* when operated by either one of the stops *e*, rides in the spiral slots of the cam *c* to operate the rods *b*² *b*³ and reverse the positions of the vanes *b* *b'*.

I claim:

1. The combination with an oscillatory mounted motor driven fan, of a pair of vanes pivotally mounted on opposite sides of the axis of rotation of the fan and disposed in planes at right angles to each other, said vanes being adapted to alternately present their faces and edges to the current of air from said fan, and means controlled in the oscillation of said fan for operating said vanes.

2. The combination with a reciprocally mounted motor driven fan, of vanes carried by the fan before the fan blades and disposed in planes at right angles to each other, on horizontal axes, said vanes being adapted to alternately screen the sides of the front of said fan, to oscillate the same, and means for reversing the positions of said vanes in the oscillation of said fan.

3. The combination with a reciprocally mounted motor driven fan, of a casing for the fan blades, vanes disposed in planes at right angles to each other mounted on horizontal axes upon the casing, said vanes being adapted to alternately assume vertical and

horizontal positions respectively, to alternately screen the sides of the front of said fan, a cam, a lever adapted to engage said cam to operate said vanes, and means for 5 operating said lever as the fan approaches the limit of its oscillation in either direction.

4. The combination with a reciprocally mounted motor driven fan, of a casing for the fan blades, vanes disposed in planes at 10 right angles to each other and mounted in horizontal axes, said vanes being adapted to alternately screen the sides of the front of said fan, a spiral cam, a pendulum lever adapted to engage said cam to operate said 15 vanes, and arms carried by the base of the fan for operating said lever as the fan approaches the limit of its oscillation in either direction.

5. The combination with a pivoted motor

driven fan, of a guard casing *a*, vanes *b* *b'*, 20 for alternately screening the sides of the front of the fan, pivoted rods *b²* *b³* for said vanes, a spiral-cam uniting the inner ends of said rods, a lever *d* adapted to ride in slots in said cam to operate said vanes, arms *e* *e* for 25 operating said lever, and cross bars *a'* *a'* of said casing, adapted to coöperate with said lever and arms to limit the movement of the fan.

In witness whereof, I hereunto subscribe 30 my name this 23 day of March, A. D. 1906.

ERASTUS W. WILLARD,
*Administrator of the estate of Harold R. Well-
man, deceased.*

Witnesses:

JAMES G. ELWOOD,
W. E. DEAN.
